B. S. MOORE

LOCOMOTIVE FRAME

Filed Jan. 20, 1922

UNITED STATES PATENT OFFICE.

BENJAMIN S. MOORE, OF WILKINSBURG, PENNSYLVANIA, ASSIGNOR TO WESTINGHOUSE ELECTRIC & MANUFACTURING COMPANY, A CORPORATION OF PENNSYLVANIA.

LOCOMOTIVE FRAME.

Application filed January 20, 1922. Serial No. 530,564.

To all whom it may concern:

Be it known that I, BENJAMIN S. MOORE, a citizen of the United States, and a resident of Wilkinsburg, in the county of Allegheny and State of Pennsylvania, have invented 5 a new and useful Improvement in Locomotive Frames, of which the following is a specification.

My invention relates to electric locomotives; more especially to locomotive beds which are mounted on wheel axles and support the locomotive body.

It is among the objects of this invention to provide a locomotive-bed structure comprising a pair of castings which may be easily machined and readily assembled to provide a rigid structure.

It is another object of this invention to provide a design of the above designated 20 type in which the various operating parts, such as journal supports shall be embodied as a part of the frame and which shall permit the several parts to be assembled with assurance of obtaining accurate alignment 25 and maintenance thereof after assembly.

It has been the practice to make locomotive beds of separately formed parts joined together by bolts, cross-ties, and the like, which required considerable labor and expense in machining and manufacture and 30 which necessitated an excessive number of joints which were subjected to vibration and strain and, consequently, became loosened.

Another type of construction suggested 35 was to form the locomotive beds of a single unitary casting which, because of its bulk, was difficult to cast and offered extreme difficulty in handling and machining.

In my present invention, I propose to 40 form the locomotive bed of a pair of castings, provided with a longitudinal joint at the center line thereof, which offer no difficulties in casting and facilitate the handling and machining during the manufacturing 45 process.

In the accompanying drawing constituting a part hereof and in which like reference characters designate like parts;

Figure 1 is a plan view of a portion of a 50 locomotive bed formed in accordance with my invention;

Fig. 2 is a view thereof, in side elevation; and

Fig. 3 is a cross-sectional view taken along the line III—III of Fig. 2.

The members 1, 1 constitute the side frames having transversely depending cradle members 2 formed integrally therewith and having transversely depending end portions 3 which constitute the end sills of the locomotive bed. The cradle members 2 are of semi-cylindrical shape and are provided with plane seating surfaces 4 and straight longitudinal depending flanges 5 forming a longitudinal joint along the center line of the castings which are secured together by a plurality of bolts 6. The flanges 5 are provided with a groove-and-tongue connection 7 which must be accurately machined in order to insure accurate 60 alignment of the side frame members 1.

The side-frame members 1 are further provided with depending flanges 8 along their central portions which are provided with strengthening ribs 9. The semi-cylindrical cradle members are provided with projecting lugs 10 which are accurately machined for seating the stators of the motors. The side frames are provided with a plurality of pedestals 11 having spaces 12 therein for mounting the journal boxes (not shown), and the center of the cradle is provided with a jackshaft journal support 13 which runs transversely to the frame. A pair of motor-bearing-journal supports 14 are provided in the side frames integral therewith to insure positive alignment of the motors and jack-shaft supports 13.

The cradle frame is designed to provide a rigid central support 15 having a plane surface 16 for clamping the motor stators and for securing the motor covers which are mounted thereon after the motors have been assembled in the frame.

The structure herein described may constitute but one-half of a locomotive frame, the other portion thereof being a duplicate of the portion illustrated in the drawings.

It will be readily understood from the above description of my invention that locomotive beds formed in accordance therewith provide a simple rigid structure which insures positive alignment of the motor and jackshaft bearings and which does not require additional bracing, as by separate cross ties, which was common in prior assembled

structures. It will also be noted that the metal is concentrated at a point where it is most needed and, therefore, offers the maximum strength with the minimum amount of weight.

Although I have described a specific embodiment of my invention, it will be obvious to those skilled in the art that various modifications may be made in the details of construction thereof. For instance, the various structural details may be modified to suit any given condition and the longitudinal joint may be changed from the seating flanges to interlocking flanges. These and other changes may be made in the details of construction without departing from the spirit of the invention.

I claim as my invention:

1. In a locomotive bed, a pair of substantially parallel side-frame members and transversely depending cradle members secured to said side frame members, said cradle members being secured together to provide a unitary, rigid locomotive-frame structure.

2. In a locomotive bed, a pair of substantially parallel side-frame members, transversely depending cradle members secured to said side frame members, and means for securing said cradle members together to provide a unitary, rigid locomotive-frame structure.

3. In a locomotive bed, a pair of substantially parallel side frame members, cradle members formed integral with said side frame members, and means for securing said cradle members together to provide a unitary, rigid locomotive-frame structure.

4. In a locomotive bed, a pair of substantially parallel side-frame members, cradle members formed integral with said side-frame members, and means for securing said cradle members together along a line substantially parallel to said side-frame members to provide a unitary, rigid locomotive frame structure.

5. In a locomotive bed, a pair of substantially parallel side frame members, cradle members formed integral with said side frame members, flange seats on said cradle members parallel thereto, one of said flanges having a groove formed therein and the other flange having a correspondingly shaped tongue for seating into said groove, said flanges being secured together to provide a unitary rigid locomotive frame structure.

6. In a locomotive bed, two laterally spaced side-frame members, each provided with a cradle portion extending inwardly toward a correspondingly disposed cradle portion carried by the other frame, and means for securing the said cradle portions together.

7. In a locomotive bed, two laterally spaced side-frame members, each provided with a transversely depending cradle portion extending inwardly toward a correspondingly disposed cradle portion carried by the other frame, and means for securing the said cradle portions together.

In testimony whereof, I have hereunto subscribed my name this 4th day of January, 1922.

BENJAMIN S. MOORE.
